UNITED STATES PATENT OFFICE.

JOHN E. RABER, OF CANTON, OHIO.

COAL CHUTE FOR CELLAR WINDOWS.

Application filed August 26, 1924. Serial No. 734,358.

To all whom it may concern:

Be it known that I, JOHN E. RABER, a citizen of the United States, residing at Canton, in the county of Stark and State 5 of Ohio, have invented certain new and useful Improvements in Coal Chutes for Cellar Windows, of which the following is a specification.

The invention relates to improvements in chutes, such as are used for the windows of coal cellars, and is more especially related to an improvement over my prior Patent No. 1,193,058, patented August 1, 1916.

The objects of the improvement are to 15 provide a simple and efficient construction of coal chute for a cellar window provided with a hinged sash, the chute including a hopper pivotally mounted therein and arranged to be moved into operative position 20 when the hinged sash is opened and to be moved into the inoperative position when it is desired to close the sash.

The above and other objects are attained by providing a hopper similar to the hopper shown in my prior patent above referred to, the pivotal movement of the hopper into the operative and inoperative positions being attained by a smaller mechanism than required in said patent; an elongated slot in, 30 each side wall of the hopper cooperating with the stud in the frame of the chute, to permit the desired movement of the hopper.

An embodiment of the invention thus set forth in general terms is illustrated in the 35 accompanying drawings, in which—

Figure 1 is a perspective view of a coal chute embodying the invention, showing the hopper in open or operative position;

Fig. 2, a transverse, sectional view 40 through the chute and hopper in the open position;

Fig. 3, a similar view showing the hopper partially opened;

Fig. 4, a similar view showing the hopper 45 in the inoperative position and the hinged sash in the closed position; and

Fig. 5, a section on the line 5—5, Fig. 4.

Similar numerals refer to similar parts throughout the drawing.

The frame 5 of the cellar window is preferably formed of cast iron or the like of rectangular shape, and provided with the stationary hinge ears 6 formed integrally therewith.

The sash 7 of the window is provided with the movable hinge ears 8, the hinge formed

by the ears 6 and 8 being preferably of the construction shown in my prior Patent No. 1,195,085, issued August 15, 1916.

A glass panel 9 may be provided in the sash and normally covered by a sheet metal guard 10, which may be constructed in the manner disclosed in my copending application filed of even date with the present application.

The chute proper preferably comprises a sheet metal casing 11 connected to the inner side of the window frame 5 and provided with the inclined bottom portion 12. The hopper is mounted within the window frame 70 and arranged to be normally swung into inoperative position within the casing 11, and comprises the wall 13 which constitutes the bottom of the hopper in the opened position, and the side walls 14.

An elongated, angularly disposed, slot 15 is formed in each side wall of the hopper and receives the bushing or roller 16 upon the bolt 17, which is carried in the half round projection 18 formed upon the rear 80 edge of the inturned flange 19 of the window frame.

A stop pin 20 is located upon the side wall of the hopper adjacent to one end of the slot 15 and in the normal inoperative position of the hopper this stop pin is arranged to contact with the under edge of the half round projection 18, upon the window frame, while the adjacent end of the slot engages the bushing upon the bolt 17, 90 as shown in Fig. 4.

When the hopper is in the open or operative position, as shown in Figs. 1 and 2, the same end of the slot 15 engages the bolt or stud 17 and the stop pin 20 engages the 95 upper edge of the half round projection 18 upon the window frame, the lower edge of the bottom 13 of the hopper resting against the window frame.

In moving the hopper to the inoperative 100 position, it is only necessary to push the hopper inward into the position shown in full lines in Fig. 3, the slots 15 in the side walls of the hopper, limiting the inward movement of the hopper as the opposite ends 105 of said slots engage the studs 17.

At this point it will be seen that the stop pins 20 have moved in the path of the broken line A to a point spaced from the rear edge of the flange 19 of the window 110 frame.

The hopper is then pushed inward, pivot-

ing upon the studs 17, the stop pins 20 traveling in the path of the broken line B until they engage the rear edge of the flange 19, at which time the hopper has assumed 5 the position shown in dot and dash lines in Fig. 3.

As the hopper is given a further inward movement, the stop pins 20 ride upward along the rear edge of the flange 19 in the 10 path of the broken line C, until they engage the under edge of the half round projection 18, at which time the hopper has assumed the position shown in Fig. 4, the ends of the slots 15 adjacent to the pins 20, 15 coming into contact with the studs 17.

The weight of the hopper is sufficient to hold it in this position, substantially the entire body portion of the hopper being located at one side of the pivotal point, while 20 the stop pins 20 engaging the under edges of the half round projections 18, prevent further inward movement of the hopper.

In this position, the swinging sash 7 may 25 be closed as shown in Fig. 4, and the window guard 10 lowered, permitting the light to pass through the glass panel 9 which is unobstructed by the inoperative position of the hopper.

As the hopper is mounted upon a pivotal 30 point 17, centrally located between the top and bottom of the chute, it could not swing into place within the chute if the pivotal point of the hopper were stationary. For this reason the slot 15 is provided in the 35 hopper, the shape and position of said slot permitting the hopper to describe two radii, about the pivot 17, as it is revolved upwardly into the chute, the slot accomplishing the same result which is obtained by 40 the arms in my former patent above referred to.

I claim:

1. A chute of the character described, including a window frame, a stud in each side 45 of the window frame midway between the top and bottom thereof, a hopper provided with elongated slots arranged to pivot at both ends upon said studs, and stop pins in the hopper for engagement with the rear 50 edge of the window frame.

2. A chute of the character described, including a window frame, a stud in each side

of the window frame midway between the top and bottom thereof, a hopper comprising a bottom wall and angular side walls 55 provided with elongated slots engaging said studs and arranged to pivot at both ends upon said studs, and a stop pin in each side wall for engagement with the rear edge of the window frame. 60

3. A chute of the character described, including a window frame, a stud in each side of the window frame midway between the top and bottom thereof, a hopper provided with elongated slots engaging said studs 65 and arranged to pivot at both ends upon said studs, and a stop pin adjacent to one end of each slot for engagement with the rear edge of the window frame.

4. A chute of the character described, including a window frame, a stud in each side of the window frame midway between the top and bottom thereof, a hopper comprising a bottom wall and angular side walls 75 provided with elongated slots engaging said studs and arranged to pivot at both ends upon said studs, and a stop pin in each side wall adjacent to one end of each slot for engagement with the rear edge of the window frame. 80

5. A chute of the character described, including a window frame provided with a rearwardly disposed projection upon each side midway between the top and bottom, a stud upon each of said projections, a 85 hopper including a bottom wall and angular side walls provided with elongated slots engaging said studs and arranged to pivot at both ends upon said studs, and a stop pin 90 near one end of each slot for engagement with the rear edge of the window frame and the adjacent projection.

6. A device of the character described including a chute, a stud in each side thereof midway between the top and bottom of the chute, and a hopper provided with slots 95 closed at both ends and engaging said studs and arranged to describe two radii about the studs in moving the hopper from operative to inoperative position or vice versa. 100

In testimony that I claim the above, I have hereunto subscribed my name.

JOHN E. RABER.
